COMBINATION BULB AND PISTON SYRINGE OR SIMILAR ARTICLE

Richard E. Ericson, Keene, N.H., assignor to Elliot Laboratories, Inc., a corporation of New Hampshire

Filed Aug. 27, 1969, Ser. No. 18,877

Term of patent 14 years

Int. Cl. D24—03

U.S. Cl. D83—12

FIG. 1 is a front view in elevation of a combination bulb and piston syringe showing my new design.

FIG. 2 is a view in perspective thereof.

FIG. 3 is a view in perspective taken from another angle.

I claim:

The ornamental design for a combination bulb and piston syringe or similar article, substantially as shown and described.
